UNITED STATES PATENT OFFICE.

LEON M. CABANA, OF BUFFALO, NEW YORK.

DESIGN FOR A SPOKE-WRENCH.

SPECIFICATION forming part of Design No. 32,744, dated May 29, 1900.

Application filed May 3, 1900. Serial No. 15,426. Term of patent 14 years.

To all whom it may concern:

Be it known that I, LEON M. CABANA, a citizen of the United States, residing at Buffalo, Erie county, New York, have invented and 5 produced a new and original Design for Spoke-Wrenches, of which the following is a specification, reference being had to the accompanying drawings, forming part thereof.

Figure 1 is a perspective view of the wrench.
10 Fig. 2 is an end elevation of the same.

As shown in the drawings, the leading or material feature of my design consists of a disk-shaped end having a surface that is slightly convex and a handle or grip portion 15 which is slightly flattened upon its sides and

corrugated, as shown in Fig. 1. The converging slot, which extends longitudinally through the grip slightly past the center, has its opening upon the side of the wrench in such manner that the corrugated surfaces are 20 unbroken.

Having described my invention, what I claim as new, and desire to secure by Letters Patent, is—

The design for a spoke-wrench as herein 25 shown and described.

LEON M. CABANA.
